United States Patent Office

Des. 197,191
Patented Dec. 24, 1963

197,191

BOTTLE

Howard A. Anderson, Pittsburgh, Pa., assignor to Bissell
Inc., Grand Rapids, Mich., a corporation of Michigan

Filed Feb. 6, 1963, Ser. No. 73,465

Term of patent 14 years

(Cl. D58—6)

FIG. 1.

FIG. 2.

FIG. 3.

FIG. 4.

I claim:

The ornamental design for a bottle, substantially as shown and described.
